DESIGN FOR A CAP

Ruby Lipton, New York, N. Y.

Application March 18, 1937, Serial No. 68,265

Term of patent 14 years

To all whom it may concern:

Be it known that I, Ruby Lipton, a citizen of the United States, residing in New York, county and State of New York, have invented a new, original, and ornamental Design for Caps, of which the following is a specification, reference being had to the accompanying drawing, forming part thereof.

Fig. 1 is a side elevation of the cap of this invention shown lying on a flat surface and showing the opening in the crown and its relation to the remainder of the cap.

Fig. 2 is a view in side elevation of the cap of this invention shown lying on a flat surface, showing the opposite side to that of Fig. 1 and showing the opening in the crown and its relation to the remainder of the cap.

Fig. 3 is a side elevation of the cap of this invention shown as lying on a flat surface showing the relation of the adjustable crown to the remainder of the cap when the opening is closed, and

Fig. 4 is a view in side elevation of the cap of this invention shown as lying on a flat surface showing the relation of the adjustable crown to the remainder of the cap when the opening is closed, this view showing the opposite position to that shown in Fig. 3.

I claim:

The ornamental design for a cap, substantially as shown and described.

RUBY LIPTON.
